UNITED STATES PATENT OFFICE

CLARENCE A. CHARBENEAU, OF MOUNT CLEMENS, MICHIGAN

BOOKMARKER

Application filed September 25, 1931. Serial No. 565,130.

This invention relates to bookmarks, and particularly to bookmarks comprising a plurality of markers insertable at selective places in a book, held normally in place by a common means and readily removable individually.

An object of the invention is to provide a plurality of markers consisting of elongated strips of thin flexible sheet material adapted to be positioned between the leaves of a book, projecting beyond the top and bottom edges of said leaves, and to form the end portions of said strips with hooks, such as will permit quick and easy attachment of the strips to, and their removal from, a suitable cord or cords extending from cover to cover across the top and bottom edges of the book.

Another object is to provide a pair of less flexible supporting strips of sheet material, attachable to the covers of a book, preferably upon the inner faces of said covers, and to form said strips with stamped-out projections for retaining and properly positioning a cord, or cords, to hold said marker strips in place.

A further object is to form said cover-engaging pair of strips with stamped-out projections adapting said strips to be quickly and easily secured to or removed from the covers.

Still another object is to form one of said pair of supporting strips with a pair of stamped-out projections for quick detachable engagement by the ends of a cord to which the marker strips are attachable.

These and various other objects the invention attains by the construction hereinafter described, and illustrated in the accompanying drawing, wherein:

Fig. 1 is a perspective view of a book, showing the herein-disclosed bookmark in use.

Fig. 2 is another view of said book and bookmark, looking edgewise at the leaves, and showing the covers bent to extend oppositely from and transversely to the leaves, the outer portions of said covers being broken away.

Fig. 3 is an elevational view of the book and bookmark, with the leaves and one of the covers parallel and the other transverse to the plane of the drawing, and the leaves positioned against that cover which parallels the

plane of the drawing.

Fig. 4 is a cross sectional view, taken on the line 4—4 of Fig. 2, showing an end portion of one of a pair of strips by which the marker is attachable to the covers of a book.

In these views, the reference characters 1 and 2 designate respectively the leaves and the covers of a book.

Secured to the covers 2 upon their inner faces, and extending from top to bottom of said covers, is a pair of elongated strips 3 and 4, formed of thin sheet material, preferably metal. Each of said strips is formed upon its upper and lower end portions with a pair of struck-out tongues 5, preferably triangular, projecting toward each other at a slight divergence to the body of the strip, said tongues being adapted to overlap and frictionally grip the top and bottom edge portions of the covers to hold said strips firmly in proper place against the book back, as best appears in Fig. 1. Said strips 3 and 4 terminally project slightly above and below the book for engagement by a flexible elastic cord 6, extending across the book top and bottom to connect said strips, and further extending lengthwise of said strips, its ends being secured to the strip 4 as indicated at 7, preferably by attaching said ends to a pair of triangular tongues 8 struck out of the central portion of said strip 4 and projecting toward each other.

To adapt the cord 6 to quick-detachably engage the projecting ends of the strips 3 and 4, it is preferred to form each of said ends with a keeper consisting of a small 85 struck-out tongue 9. The tongues 9 project transversely of the strips 3 and 4 toward the front edges of the covers, as best appears in Fig. 2. Each of said tongues is so angularly bent as to diverge from substantially 90 its mid point to its ends, thus forming a keeper space having a flaring entrance portion to readily admit the cord, and having a retaining portion affording free sliding of the cord, while prohibiting accidental escape of 95 the cord. The keeper tongues 9 are adequately resilient to yield freely away from the strips 3 and 4 responsive to an entering or removal stress on the cord.

Between the book leaves, at any desired 100

points, are engaged a series of elongated freely flexible marker strips 10 preferably of transparent material, such as celluloid. Said strips extend from top to bottom of the book, terminally projecting beyond the leaves similarly to the strips 3 and 4. The upper ends of each marker strip 10 are formed with elongated slots 11, each opening in a longitudinal edge of the corresponding strip and extending to the longitudinal central axis of the strip, and projecting along said axis toward the adjacent strip extremity, terminating some distance short of said extremity. The entrance portions of the slots 11 are relatively wide and merge with a gradual curvature into the rectilinear main length of said slots.

The lower ends of the strips 10 are each formed with a relatively short slot 12 having a reduced closed end portion projecting downwardly along the central longitudinal axis of the strip and having a relatively wide entrance portion opening in the edge of the strip opposite to that broken by the mouth of the slot 11, the mouth portion and closed end portions of the slots 12 merging into each other with a gradual curvature.

Each of the described markers comprises, additionally to the strip 10, an arm 13 rigidly secured at one of its ends to the strip 10, and projecting from the latter in a transverse relation thereto, its other end portion projecting slightly from between the leaves of the book and carrying a suitable reference number. Preferably, the arms 13 are formed similarly to the strips 10, of transparent sheet material such as celluloid.

In the use of the described marker, the metal strips 3 and 4 are initially engaged as described with the book covers, preferably in proximity to the book back, and the cord 6 is then slipped beneath the keeper tongues 9 extending substantially the full length of the strip 3, and extending upon the strip 4 from the tongues 9 to the tongues 8, being tied or otherwise fastened to the latter.

Any desired number of the marker strips 10 are then inserted one at a time between the book leaves at the points to be marked, their upper and lower ends being successively engaged with the top and bottom spans of the cord 6. The wide entrance portions of the slots 11 and 12 permit the extremities of the marker strips to be readily hooked upon said cord spans, and the considerable longitudinal extent of the slots 11 insures retention of the upper cord span in said slots during engagement of the lower span in the slots 12. The cord 6 is preferably sufficiently slack to avoid imposing any appreciable bending stress on the ends of the marker strips. The arms 13 of the several marker strips are so relatively offset longitudinally of the marker strips as to permit, so far as possible, the numbered extremities of the

arms 13 to be individually read without mutual interference.

A highly desirable feature of the described book mark lies in the fact that each of the individual markers is readily engaged with or detached from the cord 6 without disturbing the connection of said cord with the supporting strips 3 and 4, and without disturbance of any other of the marker strips.

Another important advantage lies in the fact that marker strips when once engaged with the cord 6 are quite securely held by the latter, so that concurrent use of a large number of the markers creates no tendency toward release of the markers.

Furthermore, the described provision for engaging the marker strips with the cord and for attaching the latter to the supporting strips 3 and 4 minimizes the time necessary for these operations, as well as avoiding accidental disengagement of the parts.

While it is apparent that the illustrated embodiment of this invention is well calculated to adequately fulfill the objects and advantages primarily stated, it is to be understood that the invention is susceptible to variation, modification and change within the spirit and scope of the subjoined claims.

What I claim is:

1. A book mark comprising two spans of flexible material, extensible substantially from cover to cover of a book across the top and bottom of the book, means for attaching said spans to the book, in proximity to the book back, and a plurality of marker strips formed of flexible sheet material, insertable at desired points between the book leaves and adapted to project above and below such leaves to engage said spans, the end portions of each marker strip being formed with slots, opening terminally in opposite lateral edges of the strip and extending from their terminal openings toward the adjacent strip extremities.

2. A book mark comprising a pair of flexible strips formed of sheet material engageable between the covers of a book, each in proximity to one of said covers, and proportioned to terminally project above and below the book, keeper tongues struck out of the projecting end portions of said strips and projecting transversely of said strips, spans of flexible material engaging said keeper tongues and adapted to extend across the top and bottom of a book from cover to cover, and a plurality of marker strips engageable between the leaves of a book and detachably engageable with said spans of material.

3. A book mark comprising an elastic cord, means for attaching the ends of said cord to a book cover, means for slidably engaging intermediate portions of the cord with each end of each cover of a book, whereby a span of said cord is extensible from top to bottom of one of said covers and spans are extensible

across the top and bottom of the book, and a plurality of flexible marker strips detachably engageable with said cross spans of the cord.

5 4. A book mark comprising a pair of strips of flexible sheet metal material engageable between the covers of a book in proximity to the book back and each in proximity to one of said covers, and proportioned to project 10 above and below the book, a pair of struck-out tongues formed upon one of said strips and projecting toward each other, a cord having end portions attached to said tongues and extending to the projecting ends of 15 the strip carrying said tongues, and adapted to extend between said strips across the top and bottom of the book, and to extend lengthwise upon the other of said strips, and means for attaching said cord to the project- 20 ing ends of both of said strips.

5. A book mark comprising two spans of flexible material extensible across the top and bottom of a book, means for attaching said spans to a book, in proximity to its 25 back, and an elongated marker strip formed of flexible sheet material having its extremities formed with a pair of slots to receive said spans, said slots terminally opening in opposite lateral edges of said strip at un- 30 equal distances from its ends and each of said slots extending toward the adjacent end of said strip.

6. A book mark as set forth in claim 5, said slots terminating in a substantially equidistant 35 relation to the strip extremities.

7. A book mark comprising a pair of strips of flexible sheet material engageable between the covers of a book, each in proximity to one of said covers and to the book back, and proportioned to project above and below the book, a pair of spans of flexible material adapted to extend across the top and bottom of a book between the projecting end portions of said flexible strips, keepers for said 40 45 spans struck out of said projecting end portions, and a plurality of marker strips engageable between the leaves of each book and detachably engageable with said spans.

8. A book mark comprising a pair of strips of flexible sheet material engageable between the covers of a book, each in proximity to one of said covers, said strips having end portions projecting beyond an end of the book, 50 means for holding said strips in the specified 55 relation to a book, a flexible cord having a portion extending across said end of the book between said projecting end portions, and having portions longitudinally extending on 60 each of said strips keepers for said cord carried by said projecting end portions, means for positioning the longitudinally extending portions of said cord upon said strips, and a plurality of flexible marker strips en- 65 gageable between the leaves of said book and

detachably engageable with the cross portion of said cord.

9. A book mark comprising a pair of strips of sheet material engageable between the covers of a book, each in proximity to one of said covers, and proportioned to terminally project above and below said book, a cord having portions extending across the top and bottom of the book between said projecting portions of the strips and having a portion 70 extending on one of said strips between its end portions, anchorage means for the ends of said cord carried by the other of said strips, keepers upon the end portions of said strips slidably engaged by said cord, and a 75 plurality of flexible markers engageable between the leaves of said book and detachably engageable with the cross portions of said cord.

In testimony whereof I sign this specification. 85
